UNITED STATES PATENT OFFICE.

EMIL J. FRANCK, OF COLLINGDALE, PENNSYLVANIA.

KNITTING-MACHINE.

SPECIFICATION forming part of Letters Patent No. 681,209, dated August 27, 1901.

Application filed October 16, 1900. Serial No. 33,409. (No model.)

To all whom it may concern:

Be it known that I, EMIL J. FRANCK, a citizen of the United States, residing at Collingdale, Delaware county, Pennsylvania, have invented certain new and useful Improvements in Knitting-Machines, of which the following is a specification.

One object of the present invention is to provide durable, efficient, and reliable mechanism adapted to accomplish the production of high-spliced heels, spliced toes, and double soles, or any or all of these.

Another object of the invention is to protect the end of the splicing-thread from wear.

Other objects of the invention are herein-after set forth, as well as its characteristics and scope, which are pointed out in the claims.

In the drawings, Figure 1 is a top or plan view of portions of a knitting-machine embodying or containing features of the invention. Fig. 2 is a side elevational view, of the same. Fig. 3 is a sectional view, drawn to an enlarged scale and illustrating the upper portion of the head, showing double-sole and high-splicing mechanism embodying features of the invention. Fig. 4 is a detached view illustrating means for bringing the last-mentioned mechanism into and out of action. Figs. 5 and 6 are respectively a plan and a sectional view of parts of this mechanism which puts in the double sole and high-spliced heel. Figs. 7 and 8 are diagrammatic plan views, the former showing the double-sole mechanism out of action and the latter showing it in action. Fig. 9 is a top or plan view showing the circular and eccentric paths which control the position of the mechanism last referred to. Fig. 10 is a view, partly in elevation and partly in section, showing

the yarn-locker and constituting an end view looking toward the left of the mechanism shown at the top of Fig. 2. Figs. 11, 12, and 13 are respectively sectional plan, side, and end views showing the cutting mechanism and yarn-guides which form part of the high-splicing mechanism. Fig. 14 is a sectional view drawn to an enlarged scale and illustrating the concentric yarn or guide tubes. Figs. 15 and 16 are views of the splicer-thread tubes, and Figs. 17 and 18 are views of the main-thread tubes.

In the drawings the various parts constituting the invention are shown in application to a machine in which the needles are operated in groups, each group containing substantially one-half of all the needles. In Fig. 8 the group 1 of needles may be designated the "instep-needles," and 2 indicates the other group of needles. The machine shown is provided with a pattern-chain 3 and with a pattern-drum 4, which are suitably rotated and arranged to cause the various parts of the machine to produce both tubular and fashion work, as required. There is also a lever 5, which is suitably shifted and which takes part in the accomplishment of these functions. This lever 5 is shifted by means of projections, as *x*, upon the walls of a groove in or on a part carried by the drum.

Having thus indicated certain parts which will enter into the description of the invention, I will now proceed with the latter.

6 is a carrier for what I shall call the "sole" and "high-spliced heel thread" 7. This carrier 6 has imparted to it a motion of rotation around the axis of the needle-cylinder as a center. As shown, this thread-carrier 6 as well as its bobbin 8 and thread-guide *a*, are mounted upon the sinker-cam 9. The carrier 6 has also imparted to it motion in respect to its fulcrum 10. The inner end of the part 6, which guides the thread, may travel a circular path 11, Fig. 7, which lies inside of the circle of needles (indicated by 12 in said figure) or it may travel a circular path (indicated by 13, Fig. 8) which lies eccentrically in respect to the circle of needles 12. As shown in Fig. 8, the thread 7 would be incorporated into the stitches formed by the needles designated 2, and it would then pass across the knitted tube, as shown at 14. Thus the portion of the tube formed by the needles 2 would contain an extra thread, and the portions of this thread indicated at 14 and which range crosswise of the interior of the tube are cut away. When the part 6 occupies the position shown in Fig. 7, the extra thread is manifestly not incorporated into the work done by any of the needles.

15, Fig. 3, is a ring that serves to hold the portions 14 of the extra thread down. The carrier 6 may be connected with its shank in such a way that it can be turned up, for example, to thread it. As shown in Figs. 5 and

.6, this is accomplished by means of the nut, spring, and slot (indicated by 16) and the clamping-jaws and screw, (indicated by 17.) The part 6 and the shaft 10, Fig. 6, and the arm 18 are movably supported by the bracket 19, and there is a spring 20, which serves to oppose centrifugal force and prevent such movements of the carrier 6 as might be caused thereby. The arm 18 is equipped with a stud 21, upon which is mounted a roller 22, Fig. 3. This roller 22 is free to rotate as well as to slide up and down on the stud 21. There are provided on the head of the machine two paths 23 and 24, constructed and arranged in such a way that when the roller 22 is traveling on one of them, 24, the extra thread is not being inserted and the thread-carrier 6 is traversing the path indicated in Fig. 7, and when the roller 22 is traversing the path 23 the thread-carrier 6 is traversing the course indicated in Fig. 8 and the extra thread is being inserted. As shown, the path 24 is circular and is arranged concentrically in respect to the needle-head, and the path 23 is also circular, but is arranged eccentrically in respect to the needle-head. The path 24 is slightly concave, so as to prevent accidental displacement of the roller 22, and at or near the point where the roller 22 is transferred from one path to the other the paths are substantially coincident, as shown in Fig. 4 and at the upper portions of Figs. 7 and 8. The roller 22 is shifted from one to the other of the paths 23 and 24 by means of a shipper 25, which is equipped with arms 26 and 27, Fig. 2, and mounted to slide on a bracket 28, fitted to the machine, Fig. 4. This shipper is normally solicited by a spring 29 downward into position for bringing the roller 22 onto the eccentric path 23. There is a lever of which one arm 30 serves to lift the shipper, as shown, by operating upon the head of an adjustable screw, and there is a bolt 31, which serves to lock the shipper in elevated position.

32 is an adjustable back-stop for the shipper. The arm 33 is shifted by one arm 34 of a bell-crank lever, which in its turn is actuated through a link 35, connected with the lever 5. The bolt 31 is actuated through a rocker-arm 36, link 37, and bell-crank 38, which responds to the pattern-chain 3. A further description of the mode of operation of this portion of the mechanism will be given in connection with the description of the operation of the complete machine. However, I will state that the described mechanism puts in the extra thread in the sole and high-heel portion or, in other words, in the tubular portions of the work, and I will now proceed to describe mechanism which puts an extra thread in the heel and toe or, in other words, in the fashion portion of the work.

40 is a take-up arm suitably supported above the machine by means of a bracket 41. This take-up arm is swung about its pivot by means of a link 42, connected with the arm

43 of the bell-crank. The take-up arm 40 is provided with an eye 44 for the extra thread and also with a spring-tension arm 45 for the main thread. 46 is a guide for this tension-arm, and 47 is a yarn-locker. There are two concentric tubes, of which the outer one, 48, stands still and of which the inner one, 49, is movable upward and downward. For this purpose it is connected by means of a link 50 with the take-up arm 40. Generally speaking and with reference to Fig. 14, the extra thread penetrates an eye 51 in the tube 48 and then travels down between the tubes 48 and 49, one portion of the outside of the tube 49 being flattened throughout its entire length, as shown at 52, for that purpose. The main thread passes through a long slot 53, which extends through the top of the inner tube 49 and then through the inner tube and out at its lower end to the ordinary thread-guide 54 of the machine.

55, Figs. 12 and 13, is a knife which serves to sever the extra thread, and 56 is a leather or similarly-faced spring-actuated holder or collar which holds the severed end of the thread upon the knife. To accommodate the knife, the lower end of the inner tube 49 is offset, as at 57, and the tube 48 is slotted at 58 to accommodate the extra thread, as shown in Fig. 13. The knife 55 is carried by a tappet-rod 59, which is operated by a tappet-arm 60, connected with the take-up arm 40. When the tube 49 is in elevated position, the main thread passes through the bottom of the slot 53 and out at the lower end of this tube 49. It therefore traverses nearly the whole length of the tube 48 in company with the extra thread, which is no longer separated from it, because the tube 49 has been practically withdrawn from the tube 48. The withdrawal of the knife 55 releases the extra thread, and it is free to join and travel with the main thread. When the tube 49 is in its lowest position, the extra thread is outside of it for substantially the whole of its length, and the main thread enters the top of the slot 53 and runs through the inner tube 49 for substantially the whole of its length, so that the threads are separated by the wall 52 and 57, and therefore are not rubbed together, so that the extra thread is not worn out.

The mode of operation of the described machine may be explained in connection with the production of a stocking, as follows: The main thread, through the ordinary operation of the thread-guide 54 and the needles and the various coöperating parts and driving mechanism, is fabricated into a tubular web, which forms the leg portion of the stocking. During this time the roller 22 runs on the concentric path 24 the shipper is held in elevated position by the bolt 31, and the take-up arm 40 occupies the position shown in Fig. 2 and its extra thread is held at its end by the knife 55. As the stocking approaches the heel portion and is completed down to the point where the high splice for the heel is to

occur a suitable projection on the pattern-chain 3 actuates the parts 38, 37, and 35 in such a way that the bolt 31 is withdrawn, thus permitting the spring 29 to drop the shipper 25 downward, so that the arms 26 and 27 solicit the roller 22 onto the eccentric path 23, and under these circumstances the thread-carrier 6 lays in the extra thread in the manner hereinabove described during the formation of an appropriate number of courses. In this way the high-spliced heel itself is made. Upon its completion the various parts of the machine are shifted so as to fashion what in the stocking becomes the true heel portion. The part 5 is shifted during this operation and caused to draw the arm 34 toward the left in Fig. 2 and the arm 43 downward. The result of this is that the arm 30 lifts the shipper and returns the wheel 22 to its concentric path 24, it being understood that the bolt 31 has been previously withdrawn by reason of the fact that the pattern-chain in its travel has permitted the parts connected with the bolt to make the movements necessary for this purpose. Thus the carrier 6 is thrown out of action. The movement of the arm 43 causes the arm 60 to operate on the tappet-rod and shift the blade 55 so as to release the end of the extra thread. At the same time the take-up arm 40 lifts the movable tube 49, thus releasing the extra thread in the manner described and permitting it to travel along with the main thread. A projection on the arm 61 frees the tension-spring and the counterweight 62 facilitates movements of these parts. The tension-spring 45 being free performs its ordinary function, and the arm 40 in lifting carries with it the eye 44, and thus compensates for the reciprocating motion of thread-guide 54. Under the conditions last described the heel is fashioned and the extra thread is laid in by the thread-guide 54. Upon the completion of this operation the change back to circular work involves the movement of the lever 5 in reverse direction, thus shifting the arm 34 toward the left, Fig. 2, so that it clears the arm 33 and permits the arm 30 and carrier 25 to drop under the influence of the spring 29, so that the roller 22 runs onto the eccentric path 23, and thus lays its extra thread into the knitting forming the double sole. At the same time the parts connected with the arm 43 are returned to the position shown in Fig. 2, with the result that the extra thread is cut off and held separate from the main thread, as has been described. Upon the completion of the double sole fashioned work is again produced, as has been described in connection with the fashioned heel, except that the pattern-chain operates through a suitable projection on it to shift the bolt 31 into position for locking the carrier 25 in elevated position, so that it will hold the wheel 22 on the concentric path ready for the formation of another tubular leg portion and for the repetition of the described operation.

From the foregoing description of the man-

ufacture of a stocking it will be readily understood that the machine while well adapted for the production of such articles can nevertheless be made to produce other articles without change other than adjustment of the time of operation of the various parts.

It will be obvious to those skilled in the art to which my invention appertains that modifications may be made in detail without departing from the spirit thereof. Hence I do not limit myself to the precise construction and arrangement of parts hereinabove set forth, and illustrated in the accompanying drawings; but,

Having thus described the nature and objects of my invention, what I claim as new, and desire to secure by Letters Patent, is—

1. A knitting-machine provided with a carrier for an extra thread and with truly-circular paths or guides for constraining this carrier to lay its thread clear of the needles and for causing it to lay its thread onto some of the needles, substantially as described. 85

2. In a knitting-machine a carrier for an extra thread pivoted to a revolving part of the machine, and eccentric and concentric truly-circular guides for turning said carrier on said pivot to position it, substantially as described. 95

3. In a knitting-machine an extra thread-carrier pivoted to a rotating part of the machine, a bobbin and its thread-guide applied to said moving part, a crank-arm connected with the carrier and provided with a roller, eccentric and concentric truly-circular paths or guides, and means for shifting the roller from guide to guide, substantially as described. 100

4. In a knitting-machine the combination of a needle-cylinder, a rotating part, a thread-guide pivoted to the moving part, two guides of which each is truly circular and of which one is eccentric and the other concentric in respect to the needle-cylinder, a crank-arm connected with the pivot of the carrier, and means for causing said crank-arm to travel on one or the other of the guides, substantially as described. 105

5. In a knitting-machine a thread-carrier pivoted to a rotating part, two truly-circular paths or guides arranged eccentrically in respect to each other, a crank-arm connected with the carrier and provided with a roller adapted to travel on each of said paths or guides, a shipper adapted to position said roller, and means for moving the shipper, substantially as described. 115

6. In a knitting-machine the combination of take-up mechanism, extra-thread mechanism comprising a thread-carrier pivoted to a rotating part of the machine and paths or guides for positioning the carrier, and means for bringing one of said mechanisms into and throwing the other out of action, substantially as described. 125

7. In a knitting-machine nested tubes movable in respect to each other and of which one is flattened to provide a thread-space between the tubes and of which one is longi-

tudinally slotted for the passage of a thread, substantially as described.

8. In a knitting-machine the combination of nested tubes movable in respect to each other and having a space between them and of which one is longitudinally slotted with a knife arranged to traverse the space between the tubes, substantially as described.

9. In a knitting-machine the combination of nested tubes having a space between them through which a thread may pass, a knife arranged to traverse said space, and a thread-holding device arranged to coöperate with the knife in cutting and holding a thread, substantially as described.

10. In a knitting-machine nested tubes having a thread-space between them, a knife working in said space, a thread-holding device coöoperating with the knife, and a tappet rod and arm for operating the knife, substantially as described.

11. In a knitting-machine nested tubes having a thread-space between them and of which one is slotted longitudinally and movable, a knife arranged to work in the space between the tubes, a thread-holding device

coöperating with the knife, a tappet-rod for the knife, and a take-up arm provided with a tappet-arm and connected with the movable tube, substantially as described.

12. In a knitting-machine a part adapted to rotate around the needles, a thread-carrier connected with said part, and means comprising two truly-circular guides arranged eccentrically in respect to each other for positioning the thread-carrier to cause it to lay its thread clear of the needles or onto some of them, substantially as described.

13. In a knitting-machine nested tubes through one of which the main thread may pass and between which the extra thread may be accommodated, and means for adjusting said tubes to separate said threads or permit them to travel together, substantially as described.

In testimony whereof I have hereunto signed my name.

EMIL J. FRANCK.
